CAPPING MACHINE

Stanley D. McClellan, Dearborn, Mich.

Application April 15, 1946, Serial No. 662,220

1 Claim. (Cl. 113—18)

1

This invention relates to capping machines, and in particular, to capping machines for crimping the flanged caps or covers of containers such as cans, drums or the like.

One object of this invention is to provide a capping machine operated by power for capping cans and drums in a quick and efficient manner.

Another object is to provide a capping machine which is power-operated and which is adjustable to receive and cap containers of a wide range of sizes from a large oil drum to a small can.

Another object is to provide a capping machine for cans and drums wherein the machine is provided with a conveyor whereby the can may be filled at one station and immediately capped at an adjoining station without spilling the contents by the slopping over which occurs when the filled cans are moved any considerable distance.

Another object is to provide a capping machine as set forth in the preceding objects wherein in the machine is operated by a power-driven or hydraulically or pneumatically operated plunger, thereby eliminating most of the manual labor previously connected with capping machines.

Another object is to provide a capping machine as set forth in the preceding objects wherein the container to be capped is guided into alignment with the capping mechanism and releasably held there while the capping mechanism operates to cap the container, after which a stop is removed from engagement with the container and the latter is moved along the conveyor and another container moved into position against the aligning stop which has meanwhile been moved back into operating position.

Other objects and advantages of the invention will become apparent during the course of the following description of the accompanying drawings, wherein:

Figure 1 is a front elevation of a capping machine according to a preferred form of the invention, as operated by a hydraulic or pneumatic plunger;

Figure 2 is a side elevation, partly in central vertical section and partly broken away of the capping machine shown in Figure 1, prior to the crimping operation;

Figure 3 is a horizontal section along the line 3—3 in Figure 2, with the container removed;

Figure 4 is a horizontal section through the capping mechanism, taken along the line 4—4 in Figure 2;

Figure 5 is a fragmentary vertical section taken along the line 5—5 in Figure 4, showing the position of the crimping mechanism after the crimping operation; and

2

Figure 6 is a fragmentary side elevation, partly in central vertical section of a cam-operated modification of the upper portion of the capping machine shown in Figures 1 to 5 inclusive.

Referring to the drawings in detail, Figures 1 and 2 show a preferred form of the capping machine of this invention as including a base 10 having a stanchion or upright 11 secured thereto. The stanchion 11 is of I-section and is provided with a reinforcing web 12 rising from the base up the rearward flange 13 thereof. The forward flange 14, which is joined to the rearward flange 13 by a web 15, is machined along its front surface 16 and rearward edge portion 17 (Figure 3) to form parallel guideways for a work supporting unit, generally designated 18 and an operating unit, generally designated 19, which in turn supports and actuates the capping unit, generally designated 20. The latter operates upon containers such as cans, drums or buckets, generally designated 21.

The work supporting unit 18 consists of a vertically adjustable bed 22 having a vertical arm portion 23 extending above and below the horizontal portion 24 thereof and having a machined longitudinal slot 25 of substantially the same dimensions as the forward flange 14 so as to reciprocate vertically therealong. The arm portion 23 is retained in position by retaining plates 26 bolted thereto as at 27 and engaging the machine portions 17 of the flange 14, and is held in its adjusted position by bolts 28. The horizontal and vertical portions 23 and 24 are interconnected by integral side webs 28a.

The horizontal portion 24 of the bed 22 is provided with an approximately rectangular central opening 29 through and over which a combined stop and conveyor unit 30 extends. The latter consists of a rectangular framework 31 of angle members having side members 32 interconnected by cross members 33 (Figures 2 and 3). The side members 32 are provided with longitudinal slots 34 (Figure 3) through which pass bolts 35 for holding the framework 31 in an adjusted position, depending upon the size of the container 21 to be capped. The side members 32 are also bored at intervals as at 36 to receive the axles 37 of conveyor rollers 38, rotatably supported upon the framework 31. Secured as at 39 to and depending from the framework 31 is an angle bracket 40 which is bored to receive a pivot bolt 41 (Figures 1 and 2) and which also has a hole 42 at its lower end. Pivotedly mounted upon the pivot bolt 41 is a bell crank lever 43, the short arm 44 of which is provided with a hole 45 at its lower end. A tension spring 46 is anchored at its opposite ends to the holes 42 and 45 and serves to urge the long arm 47 upwardly, together with a stop 48 rising from the upper edge thereof and 60 extending between a pair of the rollers 38.

Rising from the horizontal portion 24 of the bed 22 near the corners thereof are four integral posts 49, the upper ends of which are provided with threaded bores 50 to receive cap screws 51. Secured to the posts 49 are supporting arms 52 (Figure 3) having longitudinal slots 53 through which the cap screws 51 pass. Secured to the inner ends of the arms 52 are bent guide rails 54 having their points 55 of nearest approach approximately at the midpoints thereof.

The operating unit 19 includes an approximately rectangular bracket 56 (Figure 2) having a vertical rear wall 57 provided with a machined slot 58 similar to the slot 25 and having similar retaining plates 59 bolted thereto as at 60. Locking bolts 61 are similarly threaded through the vertical wall 57 in a manner similar to the bolts 28. In this manner, the bracket 56 is adjustable vertically along the stanchion 11 in a manner similar to the bed 22.

Secured as at 62 to the forward wall 63 of the bracket 56 is a cylinder 64 having a cylinder bore 65 closed at its upper end by a cylinder head 66. The lower wall 67 of the cylinder 64 is provided with a bore 68 and an aligned counterbore 69 for the passage of a piston rod 70 connected to a piston 71 reciprocably mounted in the cylinder bore 65. The counterbore 69 receives an annular packing 72 compressed by a flange 73 threaded into the counterbore 69, and surrounding the piston rod 70 to prevent leakage therearound.

The cylinder 64 is provided at its opposite ends with ports 74 and 75 from which conduits 76 and 77 lead respectively to a four-way valve 78 to which are connected the supply and discharge conduits 79 and 80 connected to a conventional hydraulic pump and reservoir (not shown), or to a source of compressed air if it is desired to operate the piston 71 pneumatically. Such hydraulic and pneumatic circuits are conventional and their details form no part of the present invention.

The flow of pressure fluid through the four-way valve 78 is controlled by a valve stem 81 upon which is mounted a rotary valve member 82 having curved passageways 83 and 84 therein (Figure 1). Mounted on the outer end of the valve rod 81 is a crank arm 85 to which is pivotally connected a link 86, the lower end of which is pivotally connected to a hand lever 87 pivotally mounted at 88 upon a bracket 89 bolted to and extending forwardly from the forwardly projecting portion 90 of the bracket 56. Similarly, the valve 78 is mounted upon a bracket 91 bolted to the cylinder 64. A spring 92 anchored at its upper end to the bracket 91 and at its lower end to the clamp 93 mounted on the link 86, serves to urge the latter upward (Figure 1).

The forwardly projecting portion 90 of the bracket 56 is provided with a vertical bore 94 (Figure 2) within which is reciprocably mounted a hollow plunger 95 provided with a longitudinal bore 96, the upper end of which is threaded as at 97 to receive the enlarged threaded lower end 98 of the piston rod 70. The hollow plunger 95 is also provided with a reduced diameter bore 98a coaxial with the bore 96. Reciprocably mounted in the bores 98a and 96 are a shaft 99 and an enlarged head or piston 100 mounted on the upper end thereof. The lower end of the shaft 99 is tightly secured within a bore 101 of a spider 102, the arms of which are connected

at their outer ends to a hold-down ring 103 provided with spaced radially projecting yoke portions 104. Mounted in the latter are pivot pins 105 upon which are pivotally mounted a plurality of crimping levers 106, the lower ends of which are provided with inwardly extending arcuate crimping fingers 107 (Figures 2, 4 and 5). The upper ends of the levers 106 are provided with yoke portions 108 carrying pivot pins 109 to which are connected links 110, the upper ends of which are pivoted to pivot pins 111 mounted upon yoke ears 112 secured to and integral with the hollow plunger 95.

The modification shown in Figure 6 is generally similar to the preferred form shown in Figures 1 to 5 inclusive, and similar parts are similarly designated. In this modification, however, the machine is operated mechanically rather than hydraulically or pneumatically, and for this purpose the bracket 56 is provided with an upper forwardly projecting portion or shelf 113 upon which is mounted a reduction gear box 114 having an input shaft 115 carrying a pulley 116 for connection to an electric motor or other suitable power source. The reduction gear box 114 is of a conventional type and contains a conventional clutch (not shown), actuated by the operating rod 117 carrying a crank arm 118 pivotally connected to a link 119, the lower end of which is pivotally connected to a hand lever 120 pivotally mounted as at 121 upon the lower forwardly projecting portion 90 of the bracket 56. The shelf 113 is also provided with a bearing boss 122 which rotatably supports a cam shaft 123 which constitutes the output shaft of the reduction gear box 114. Mounted on the cam shaft 123 is a cam 124 engaging a follower 125 on the upper end of the piston rod 70. A spring 126 similar to the spring 92 and similarly secured as at 127 to the link 119, urges the latter upward. The remaining portions of the machine are similar to the construction shown in Figures 1 to 5 inclusive and are similarly designated.

Prior to the operation of the machine, the latter is adjusted to accommodate the particular size of container 21 to be capped. If the container is a tall one, the bolts 28 are loosened and the bed 22 lowered to a location near the base 10, whereupon the screws 28 are tightened. The bracket 56 is also raised to a sufficient height along the stanchion 11 by loosening the bolts 61, then retightening them in their adjusted position. When properly adjusted, the holdown ring 103 is easily movable into engagement with the cover or cap 130 of the container 21, the edge 131 of which is rolled over to receive the flanged edge 132 of the cap 130 superimposed upon it. The guide rails 54 are adjusted inwardly or outwardly so that their midportions 55 engage the side walls 133 of the container 21 when the latter is centered upon the axis of the plungers 70 and 95, whereupon the clamp screws 51 are tightened. The clamping bolts 35 are now loosened and the framework 31 moved bodily to the right (Figure 3) until the stop 48 engages the container side wall 133 while it is still in its centered position, whereupon the clamping bolts 35 are tightened. The machine is now ready for operation and will accommodate any number of containers 21 of the size for which the machine has been adjusted in the foregoing manner.

A container 21 which has just been filled with the contained material, such as paint, is slid manually from the filling station (not shown)

over the rollers 38 until it comes to rest against the stop 48 and between the midportions 55 of the guide rails 54 (Figure 3), a cap 130 meanwhile having been placed over the upper edge 131 of the container 21. The hand lever 87 (Figure 1) or 120 (Figure 6) is then pulled downwardly, operating either the valve 78 or the clutch within the reduction gear box 114. In either case, the piston rod 70, hollow plunger 95 and headed plunger 99 descend, carrying with them the capping unit 20.

The capping unit 20 continues its downward motion until the holddown ring 103 encounters the cap or cover 130, whereupon it comes to a halt. The hollow plunger 95 continues its downward motion, however, causing the crimping levers 106 and crimping fingers 107 to move inwardly, crimping the flange 132 around the rolled edge 131 of the container side wall 133 (Figure 5). The hand lever 87 or 120 is then shifted upward, causing the piston rod 70 and the capping unit 20 to be raised out of engagement with the container 21. The hollow plunger 95 and piston 100 thus form a sliding cushioning lost-motion connection between the crimping device 106, 107, 110 and the holddown device 102, 103. This lost-motion connection widens the range of action and consequently the flexibility of the capping unit 20 because of the wide range of motion provided by the piston 100 reciprocating in the elongated cylinder bore 96. The cylinder or hollow plunger 95 is moved downward relatively to the piston 100 by the reciprocation of the rod 70, the air entrapped above the piston 100 in the bore 96 providing a pneumatic cushion which lessens the shock of operation of the capping unit 20.

The operator now pushes down with one hand on the hand lever 47 (Figure 2), causing the stop 48 to move downwardly between the rollers 38, and with his other hand pushes the capped container 21 out of the way toward its next station to the left (Figure 1), and then releases the hand lever 47 so that the stop 48 returns to its raised position. The operator then places another cover 130 upon another filled container 21 from the filling station at the right (Figure 1) into position between the guide rails 54 against the stop 48. He again shifts the hand lever 87 or 120 downward, repeating the previous operation and capping the second container 21. The operation can be repeated for any desired number of containers and the machine may then be readjusted to accommodate a different size of container by making the adjustments previously described.

While I have shown and described my invention in detail, it is to be understood that the same is to be limited only by the appended claim, for many changes may be made without departing from the spirit and scope of my invention.

What I claim is:

A capping machine for crimping the edge flange of a cover around the rim of a container, comprising an upright, a container holder disposed adjacent said upright, a support connected to and extending horizontally from said upright above said holder, a plunger mounted on said support for reciprocation vertically relatively to said support, power-operated means for reciprocating said plunger, and capping mechanism connected to and depending from said plunger, said capping mechanism having a hold-down device engageable with said container cover, a crimping device comprising levers pivotally mounted on said holddown device and links pivotally interconnecting said plunger and said levers, said levers being movable horizontally by said links into crimping engagement with said cover flange and container in response to the reciprocation of said plunger in one direction, and a lost motion cushioning connection interposed between said devices and including a cylinder member with a cylinder bore therein and a piston reciprocably mounted in said cylinder bore, one of said members being connected to said plunger and to said crimping device and the other member being connected to said holddown device.

STANLEY D. McCLELLAN.
